UNITARY VACUUM TUBE STRUCTURE

Roger M. Wise, Emporium, Pa., assignor to Hy-grade Sylvania Corporation, Salem, Mass., a corporation of Massachusetts

Application September 10, 1932, Serial No. 632,569

4 Claims. (Cl. 250—27.5)

This invention relates to vacuum tubes and has for its principal object to provide a means to mount the elements in a vacuum tube whereby they form a single unit which is easily supported upon the press.

Another object of the invention is to provide a unitary structure for vacuum tube elements in which the elements may be spaced in very close proximity with each other without any danger of touching.

Another object of the invention is to provide a means to support a filament in a vacuum tube in such a manner that it cannot touch the adjacent element.

Other objects of the invention and objects relating particularly to methods of manufacturing and assembling the various parts will be apparent as the description of the invention proceeds.

One embodiment of this invention has been illustrated in the accompanying drawing, in which

Fig. 1 is a front elevational view of a vacuum tube according to my invention;

Figs. 2, 3, 4 and 5 are upper perspective views 25 of the parts of the vacuum tube of Fig. 1 in "exploded" form; and

Fig. 6 is a lower perspective view of the parts shown in Fig. 4.

The drawing shows a vacuum tube 10, comprising two triode units, 11 and 11', each comprising a filamentary cathode, 12 or 12', a control grid structure, 13 or 13', and an anode, 14 or 14'.

These triode units are mounted on upper and lower insulating disks, 15 and 16 respectively and all of the above mentioned elements are supported by support rods 17 and 17' on stem 18.

Support rods 17 and 17' are provided with lead wires 19 and 19' which provide external 40 terminals for anodes 14 and 14' respectively.

Support wires 20 and 20' serve to connect the grid structures 13 and 13' to their respective external leads 21 and 21'. Support wires 22 and 22' serve to position the triode structures 45 along the rods 17 and 17', and to connect filaments 12 and 12' to the external energizing leads 23 and 23'.

In the structure shown the filaments 12 and 12' are connected in parallel to leads 23 and 50 23', but a series connection could be used if desired.

Filaments 12 and 12' are shown as inverted V-shaped elements which are supported by hooks 24 and 24' respectively which hooks are mounted 55 on posts 25 and 25'. Posts 25 and 25' may be

mounted on the upper insulating disk 15 in any suitable manner. In this instance the posts are provided with heads 26 and 26', and are inserted in apertures 27 and 27' in disk 15. Flanged collars 28 and 28' are then secured to the posts 5 closely adjacent the surface of disk 15.

Filaments 12 and 12' pass through apertures 29, 30, 29' and 30' in lower disk 16, adjacent the points at which they are connected to support wires 22 and 22'.

The grid structure 13 or 13' for each triode is a dual structure comprising inner winding 31 or 31' and outer winding 32 or 32'. In the drawing the lower portion of winding 31' is shown cut away from its side rods 33' and 34' and the upper portion of outer winding 32' is shown cut away from its side rods 35' and 36', for purposes of clarity. However in the complete vacuum tube, the windings 31' and 32' are coextensive between the disks 15 and 16. The purpose of 20 the dual grid structure is to enable a high amplification constant to be obtained in a simple structure, while avoiding high cathode-grid current when either grid is positive with respect to its cathode.

The grid side rods, 33', 34', 35' and 36' are inserted in apertures 37' and 38' in disk 16 as shown in the drawing, and also in apertures 39' and 40' in disk 15. Apertures 37' and 40' may be provided with webs 41' and 42' as shown, to 25 laterally position the two grids 31' and 32'.

Each anode or plate, 14 or 14' is provided with lower ears 43 and 44 or 43' and 44', and with upper ears 45 and 46 or 45' and 46'. The lower ears 43' and 44' are adapted to be inserted and 35 clinched in apertures 47' and 48' in lower disk 16, and the upper ears 45' and 46' in apertures 49' and 50', provided for that purpose.

The lower disk 16 is provided with split eyelets 51 and 51', mounted in apertures 52 and 52', 40 which, when assembled, surround support rods 17 and 17' and are secured thereto.

In preparing for assembly, the stem, with its six support wires is provided, and the support wires 20 and 20' are cut and bent as shown in 45 Fig. 5. Support wires 22 and 22' are cut, and bent, as shown, so that their upper surfaces are parallel to the lower disk 16 in assembled position.

Eyelets 51 and 51' are mounted in disk 16. 50 Eyelets 53 and 53' are mounted in apertures 54 and 54' in upper disk 15. Posts 25 and 25' are mounted on disk 15 in the manner described above.

Filaments 12 and 12' are inserted through 55

apertures 29, 30, 29' and 30'. Grids 31, 32, 31' and 32' are then mounted on disk 16 in apertures 37, 38, 37' and 38'. Plates 14 and 14' are then mounted on disk 16 by inserting ears 43, 44, 43' and 44' in apertures 47, 48, 47' and 48' and clinching them therein.

Disk 15 is then applied, and the upper plate ears 45, 46, 45' and 46' bent over to secure the disk. The assembly of the filament, grid and plate elements, with the insulating disks may then be slipped over the support rods 17 and 17'.

Filaments 12 and 12' are then welded to support wires 22 and 22'. The unit structure is then forced down until the disk 16 contacts with the horizontal portion of support wires 22 and 22'.

The upstanding portions of eyelets 51, 51', 53 and 53' are then clamped or welded to the support rods 17 and 17'. Grid connecting wires 20 and 20' are then connected to grids 13 and 13'. Plate connecting wires 55 and 55' are then welded to connect plate ear 43 to rod 17 and plate ear 43' to rod 17'.

Hooks 24 and 24' are passed within their respective filaments 12 and 12' and secured to the posts 25 and 25'.

Stem 18 carrying the above described structure is then sealed in bulb 56, and is ready to be exhausted and mounted in base 57.

As the plates and grids are assembled in fixed relation to each other before the unit is mounted on the stem, the unit may be inspected and gauged from either end with convenience. My device is further distinguished from those of the prior art in that the relation between the grids and plates is not disturbed when the unit is mounted on the stem and secured thereto. Particularly, the positions of the plates are not disturbed when the electrical connections are made, as no rigid elements are attached thereto. As all the elements are secured together in the absence of the support rods, there is little tendency towards relative movement between the elements as a result of mechanical shock.

This tube is particularly adapted to "class B" amplification as the grids draw a minimum of current, and are less apt to interfere in the elec-

tron stream than in the conventional triode. As substantially no energy is being dissipated by one triode unit while the other is operating, a structure of the type described is adapted to provide much more output power than two triodes in a single bulb, operating as "class A" amplifiers, and dissipating energy continuously from both elements.

While one embodiment of my invention has been described, many other forms are useful, and the scope of my invention is limited only by the appended claims.

I claim:

1. A vacuum tube comprising a bulb enclosing a pair of triode amplifying units, each of said units comprising a cathode, a signal control grid structure, and an anode, said grid structures being electrically independent of each other and said anodes being electrically independent of each other, said grid structures each comprising a plurality of co-axial, coextensive flattened helical windings.

2. A vacuum tube comprising a bulb enclosing two triode units, each of said units comprising a cathode, a signal control grid structure, and an anode, said signal control grid structures being electrically independent of each other and said anodes being electrically independent of each other, said grid structures each comprising a plurality of coextensive foraminous members.

3. An amplifier tube for class "B" amplification comprising a pair of amplifying units in a common envelope, each of said units including an anode, a signal control grid, each grid comprising coaxial elements at least as long as said anodes and adapted to dissipate a substantial amount of heat.

4. A vacuum tube for class "B" amplification comprising a bulb enclosing a set of electrodes, said set including an electron emitting cathode, an anode and a unitary signal control grid structure positioned between said cathode and anode, said control grid structure consisting of a plurality of coaxial coextensive foraminous members.

ROGER M. WISE.
